TIME SIGNALING SYSTEM

Harry E. Hershey, Oak Park, Ill., assignor, by
means assignments to Associated Electric
Laboratories, Inc., Chicago, Ill., a corporation
of Delaware

Application May 18, 1931. Serial No. 538,153

29 Claims. (Cl. 179—2)

The present invention relates in general to time signaling systems, being concerned more particularly with a time signaling device for telephone systems. Reference is made here to the

5 John I. Bellamy et al. application, Serial No. 478,324, on which this invention is an improvement.

The object of the invention, broadly stated, is the provision of new and improved circuits and 10 apparatus for transmitting the time of day to subscribers in a telephone system by means of chimes or gongs. The subscribers, upon being connected to the time signaling device, will be under the impression that they are listening to 15 a grandfather's clock in the telephone exchange striking out the hours and minutes.

One feature of the invention is the arrangement for providing an efficient and reliable arrangement for transmitting the sound of the 20 chimes to the connected subscriber.

Another feature is the arrangement for registering certain hours of the day by means of a 25 step-by-step rotary switch and for registering the remaining hours of the day by means of relays, after the rotary switch has been positioned to a predetermined position.

Another feature is the arrangement provided 30 in the holding-bridge circuit for starting the transmitting portion of the time signaling device.

Another feature is the arrangement for affecting the registers to perform successive controlling operations.

Another feature is the arrangement for varying 35 the striking speed of the various chimes as desired. With this arrangement it will be comparatively easy to differentiate between the various chimes not only by the pitch but also by the frequency of the striking.

Another feature is the arrangement for connecting up the various chimes so that they may 40 be operated in any sequence or combination.

A still further feature is the arrangement for varying the length of a special tone signal which 45 is indicative of the numeral 0 or zero.

The foregoing objects and features together with others not specifically mentioned at this time will be further discussed in connection with the detailed description of the operation of the 50 various circuits.

The accompanying drawings comprising Figs. 1 to 3, inclusive, show by means of the usual circuit diagrams a sufficient amount of equipment embodying the invention to permit the 55 same to be readily described and understood.

Referring now to the drawings, in Fig. 1 is shown a holding-bridge circuit HB which is accessible to subscribers in an automatic telephone system. As many holding-bridge circuits may be provided as are required to handle the traffic to the time signaling equipment. Each holding bridge has an induction coil, similar to induction coil 39, whose secondary winding is normally associated with an artificial line. The primary 60 winding of all induction coils are connected in series and bridged across the chime circuit over conductors 40 and 41. This arrangement insures that the volume of sound, audible to the subscriber, will remain the same, irrespective of the 65 number of simultaneous connections.

Substation T is connected with the telephone exchange by line conductors 9 and 10 which terminate in line switch LS. The lineswitch, indicated in the drawings by the rectangle LS, is a switch of the well known rotary type whose wipers have no normal position and move in a forward direction only. As is well known, the function of the lineswitch is to extend its associated line to an idle first selector switch when the receiver is raised at the substation initiating a call. One of the first selector switches to which the lineswitch LS has access, in common with similar lineswitches, is indicated in the drawings by rectangle S. The selector used can be any of the standard type selectors used in regular practice, such as the selector shown in Fig. 63 and described on pages 62 to 65, inclusive, of Smith and Campbell's "Automatic Telephony", second edition, published in 1921 by 70 McGraw-Hill Book Company, Incorporated, New York. The lineswitch and selector used in a system of this kind may be any of the lineswitches or selector switches well known to the art, as these switches form no part of the invention. 75

Conductors 14, 15, and 16 of the holding-bridge circuit HB are wired to the bank contacts, such as 11, 12, and 13 of any selector switch having access to time signaling device.

The equipment shown to the right of the dotted line AA, together with the equipment shown in Figs. 2 and 3, constitutes the time signaling device. The three gongs or chimes C1, C2, and C3 are the hours, tens of minutes, and units of minutes, respectively, each of which consists of a solenoid 53 whose plunger 54 is designed to strike a tuned bar of steel 55. Above each tuned bar is a carefully designed resonance chamber 56 which acts upon a standard telephone transmitter 57. When the steel bars are struck by 100

110

their respective plungers the bar of steel of the hours gong C1 is tuned to emit a deep, mellow pitched tone, the bar of the tens of minutes gong C2 is tuned to emit a medium pitched tone, and the bar of the units of minutes gong C3 is tuned to emit a high pitched tone. The buzzer B1 transmits a special tone signal when a 0 or zero is to be transmitted.

The start relay 102 shown in Fig. 2 controls the starting of the relays and equipment for transmitting the time signals, which are continuously transmitted as long as the start relay is energized. It should be noted, however, that the registering equipment comprising the hours, tens, and units registers HR, TR, and UR (shown in Fig. 3) are continuously operated by relay 230 from ground impulses from a master clock (not shown on the drawings). The start relay 102 is operated over conductor 43 upon the seizure 20 of any holding-bridge circuit, similar to holding-bridge circuit HB, by a subscriber desiring to know the time of day. Relays 103—104, 105—106, and 107—108 are relay interrupters and each group is adjusted to operate at a different speed. Interrupter relays 103—104 are adjusted to interrupt the circuit through contacts 122 about forty times per minute, relays 105—106 are adjusted to interrupt the circuit through contacts 126 about eighty times per minute, and relays 107—108 are adjusted to interrupt the circuit through contacts 130 about one-hundred and twenty times per minute.

Relays 110—111 are sequence relays and are controlled by the sequence switch SS. The sequence switch SS is of the type which advances its wiper 133 one step upon each energization of the rotary magnet 116 and restores its wiper to its original starting position when the release magnet 117 is energized. The sequence switch SS and the sequence relays 110—111 are arranged to prepare operating circuits over the various registers HR, TR, and UR shown in Fig. 3, in the proper sequence and are also arranged to prepare the circuit for the various gongs C1 to C3, inclusive, in sequence with the circuits of the various registers. With the sequence switch SS in its first position the forty per minute interrupter, the low pitched or hour gong C1, the counting relays 201—226, and the bank of the hours register HR are in association. In its second position the eighty per minute interrupter, the medium pitched or tens of minutes gong C2, the counting relays 201—226, and the bank of the tens of minutes register TR are in association. In its third position the one-hundred and twenty per minute interrupter, the high pitched or units of minutes gong C3, the counting relays 201—226, and the bank of the units of minutes register UR are in association. In the fourth position the release of the apparatus takes place and the sequence of operation is repeated.

The stop relay 113 is arranged to open the circuit for the counting relays 201—226, inclusive, shown in Fig. 3, when the number of chime signals transmitted to the subscriber from any one of the gongs corresponds with the setting of the associated register. Each time the stop relay is energized the sequence switch SS advances its wiper 133 one step. Relays 114 and 115 are delay relays and are arranged to control the length of the pause between the transmission of chimes from one of the gongs to the other. Relay 114 is a relay with a weighted spring combination, similar to that disclosed in Patent No. 1,641,-

256, granted to John Erickson, September 6, 1927, and can be adjusted to vary the pause between the transmission of different gongs by adjusting the weight attached to spring 151. Following the energization of the stop relay 113 after each signal is transmitted, relay 114 is energized and causes the weighted spring to vibrate. The vibrating contact does not close a circuit to relay 115 until it comes to rest, and in this way provides the necessary delay between the transmission of chimes from each of the different gongs.

Fig. 3 shows three registers, the hours register HR, tens of minutes register TR, and the units of minutes register UR. The registers are of the eleven-point rotary switch type and are similar in construction to the twenty-five-point rotary switch disclosed in Patent No. 1,693,027, granted to John Erickson, November 27, 1928. The rotary switches are of the step-by-step type in which the wipers move in a forward direction only, and in which the wipers are advanced when the stepping magnet retracts its armature rather than when the stepping magnet attracts its armature. The units of minutes register UR advances its wipers one step each minute, the tens of minutes register TR advances its wipers one step for every ten steps of the wipers of the units of minutes register UR, and the hours register HR advances its wipers one step for every six steps of the wipers of the tens of minutes register TR. However, due to the fact that only eleven contacts are provided on the standard rotary lineswitch of this type, two relays 227 and 229 are provided to register eleven and twelve o'clock, respectively. In this way the exact time of the day is always registered on the time signaling device.

Relays 203—226 are counting relays wherein the first relay of a pair is energized by pulse over conductor 157 and the second relay of the pair is energized and locked up in series with the first when the potential for operating the first relay is removed. Each time the first counting relay of a pair is energized a circuit is closed to the connected gong and when the second relay of the pair is energized in series with the first the circuit to the connected gong is opened and a testing circuit is closed for the stop relay 113. When the stop relay is energized over any one of these test circuits it will open the holding circuit for all of the energized counting relays.

Relays 201 and 202 are a pair of pick-up relays similar to the regular counting relays. Relay 201 closes a circuit for stepping the wiper of the sequence switch SS off-normal each time a new complete time signal is to be transmitted. Relay 200 controls a circuit for operating the tuned buzzer B1 when the tens and units of minutes registers TR and UR have advanced their wipers to their respective sixth or tenth bank contact. When the time registered is 1: 00, 1: 10, 1: 20 o'clock, etc., 2: 00, 2: 10, 2: 20 o'clock, etc., it should be understood that no chimes are transmitted to represent the zero of the time registered but that the buzzer B1 is operated to transmit a tone signal, the length of which can be varied at the terminal block TB.

In the upper right-hand corner of Fig. 3 is shown a bank of lamps, which are multiplied to the bank contacts of the three registers HR, TR, and UR. These lamps, therefore, at all times display an illuminated indication of the registered time. This bank of lamps is to be mounted in front of the wire chief or other persons

responsible for the supervision of the equipment.

In the drawings the slow-acting relays are denoted by shading the lower portion of their cores, or by making the upper portion of their cores solid black, depending upon whether the relay is merely slow-to-release or is also slow-to-operate. A shaded portion on the lower end of the core indicates that the relay is slow-to-release after its energizing circuit is opened, but is not appreciably slow-to-operate when its energizing circuit is closed. A solid black portion on the upper end of the core indicates that the relay is slightly slow-to-operate when an energizing circuit is closed in addition to being slow-to-release after its energizing circuit is opened.

The invention having been described in general, a detailed description of the operation of the apparatus shown will follow.

20 *Automatic telephone subscriber calling the time signaling device*

It can be assumed that the time signaling device is in the position shown on the drawings 25 and that an automatic telephone subscriber desires to ascertain the time of day.

When the subscriber at substation T removes his receiver a circuit is closed over conductors 9 and 10 to the lineswitch LS, which functions 30 in the well known manner and extends the connection to an idle first selector, such as S. By the dialling of the number assigned to the time signaling device, the wipers of the selector are stepped up to the proper level and are automatically rotated across the banks associating its 35 wipers with bank contacts 11, 12, and 13, assuming that the trunk connected to these contacts is idle. When the selector S associates its wipers with contacts 11, 12, and 13 of its bank, a circuit 40 is immediately closed from ground, lower winding of relay 17 of the holding-bridge circuit HB, conductor 16, bank contact 13, and lower line wiper of the selector, subscriber's loop, upper line wiper and bank contact 11 of the selector, conductor 45 14 of the holding-bridge circuit HB, upper winding of relay 17, to battery. Line relay 17 closes an obvious circuit for the release relay 18. At armature 26 and its front contact, release relay 18 grounds the release trunk conductor 15 to hold the selector and preceding switches 50 operated. At armature 24 and its front contact, release relay 18 closes a circuit for the switch-through relay 22 from ground, armature 143 and its resting contact (Fig. 2), armature 134 and its 55 resting contact, conductor 42, armature 24 and its front contact, lower winding of switch-through relay 22, armature 32 and its resting contact, resistance 31, to battery. Upon energizing, switch-through relay 22 closes a locking circuit for itself 60 over its upper winding at armature 36 and its front contact to the grounded release conductor 15, connects the secondary winding of transformer 39 to line conductors 14 and 16 at armatures 35 and 38 and their respective front contacts, and by the same action disconnects the 65 artificial line or short-circuit around the secondary winding of transformer 39 at the normally closed contacts controlled by armatures 35 and 38 and their respective front contacts. At armature 37 and its front contact, switch-through relay 22 prepares a circuit for subsequently disconnecting the subscriber from the time signaling conductors 40 and 41 and transformer 39 70 and connecting him to the busy-tone conductor as will be hereinafter described.

The holding-bridge circuit HB is now in position to permit the time signals, transmitted over conductors 40 and 41 and transformer 39, to be received by the subscriber.

80 *Transmission of time signal*

It has been mentioned before that the equipment is in the position shown on the drawings when it is seized by the subscriber. The position of the registers shown in Fig. 3 should be particularly noticed. The wipers 236—237 of the hours register HR are resting on the first set of contacts of its bank, the wipers 238—240 of the tens of minutes register TR are resting on the sixth set of contacts of its bank, and wipers 241—243 of the units of minutes register UR are resting on the first set of contacts of its bank. It can be seen, by the position of the wipers, that the time to be transmitted by the time signaling device is 1:41 o'clock.

By referring again to the energization of the release relay 18 of the holding-bridge circuit HB, shown in Fig. 1, it will be noted that a circuit is closed from ground, armature 25 and its front contact, armature 30 and its resting contact, conductor 43, armature 118 and its resting contact, winding of start relay 102 to battery. Upon energizing, start relay 102 locks itself to grounded conductor 43 at armature 119 and its front contact, and grounds conductor 58 at armature 120 100 and its front contact to start the operation of the interrupter relays 103—108, inclusive. The grounding of conductor 58 also completes a series circuit for the transmitters of the gongs C1, C2, and C3 from grounded conductor 58, variable resistance 51, one winding of the impedance coil 48, transmitters of the C3, C2, and C1 gongs in series, the other winding of the impedance coil 48, to battery. The variable resistance 51 and resistance 47 are provided to vary the volume of 110 the signal or chime transmitted by the gongs. The resistance 63 shunted around the transmitter of the high-pitched gong C3 is provided to further cut down the intensity of the signal transmitted by the high-pitched gong, which is sometimes 115 unpleasantly loud.

Returning now to the operation of the interrupter relays 103—108, inclusive, it will be seen that upon grounding conductor 58 that a circuit is closed through armature 125 and its resting contact, winding of the interrupter relay 106, to battery. Upon energizing, relay 106 closes a circuit for relay 105 at armature 128 and its front contact. Relay 105 upon energizing, opens the initial energizing circuit for relay 106 at armature 125 and its resting contact. Relay 106 restores to normal and at the same time opens the circuit of relay 105. Relay 105 restores to normal and at armature 125 and its resting contact completes the circuit again for relay 106. This inter-action of the two relays continues until ground is removed from conductor 58. The inter-action of the interrupter relays 107 and 108 is exactly the same as described in connection with interrupter 130 relays 105 and 106. It should be understood, however, that relays 105 and 106 are adjusted so that the circuit through armature 126 and its resting contact is interrupted approximately eighty times per minute, while relays 107 and 108 are adjusted 135 to interrupt the circuit at armature 130 and its resting contact about one-hundred and twenty times per minute.

The first time interrupter relay 106 is energized a circuit is closed from grounded conductor 140 58, armature 127 and its front contact, armature 150

124 and its resting contact, winding of interrupter relay 103, to battery. Relay 103 energizes and at armature 123 and its front contact, prepares a locking circuit for itself in series with the upper winding of interrupter relay 104. When relay 106 is deenergized the first time, it opens the initial energizing circuit for interrupter relay 103 at armature 127 and its front contact, and at the same time a locking circuit is closed for relays 103 and 104 from the grounded conductor 58, normally closed contacts controlled by armature 127, upper winding of interrupter relay 104, armature 123 and its front contact, winding of 103 to battery. The front contact and the normally closed contact controlled by armature 127 are so adjusted that when relay 106 falls back, the front contact is opened and the normally closed contact which has been opened by the operation of the armature 127 is closed approximately at the same time. Therefore, relay 103 does not deenergize when relay 106 falls back the first time. Relay 104, upon energizing, prepares a locking circuit for itself at armature 124 and its front contact, and by the same action opens a point in the circuit for relay 103 at its resting contact. The second time interrupter relay 106 is energized a locking circuit is closed for relay 104 from the grounding conductor 58, armature 127 and its front contact, armature 124 and its front contact, lower winding of relay 104, to battery. Relay 103 now falls back because the locking circuit in series with the upper winding of relay 104 has now been opened at the normally closed contact controlled by armature 127. The second time relay 106 falls back it opens the locking circuit for the lower winding of relay 104 at armature 127 and its front contact. Relays 103 and 104 are now in their normal position and upon the next energization of interrupter relay 106 the sequence of operation is again repeated. It can readily be seen that relay 103 interrupts the circuit through armature 122 and its resting contact just exactly half as many times as relay 106 interrupts the circuit through armature 126 and its resting contact, therefore, armature 122 and its resting contact is interrupted approximately forty times per minute.

By referring again to the operation of the start relay 102, it will be noted that it closes a circuit at armature 121 and its front contact, from ground, armature 149 and its resting contact, armature 146 and its resting contact, armature 121 and its front contact, winding of relay 101, to battery. Relay 101 operates and opens the initial energizing circuit for the start relay 102 at armature 118 and its resting contact. The operating ground for relay 101 is also extended to conductor 159 and to armatures 122, 126, and 130 of the interrupter relays.

With interrupter relay 103 in its normal position grounded armature 122 completes a circuit over its resting contact, terminals 1 and 2 of the striking speed terminal block, armature 138 and its resting contact, armature 141 and its resting contact, conductor 157, armature 250 and its resting contact, winding of pick-up relay 201, to battery. Upon energizing, relay 201 closes a circuit from ground, armature 276 and its front contact, conductor 158, armature 135 and its resting contact, winding of rotary magnet 116 of the sequence switch SS, to battery. Upon energizing, rotary magnet 116 advances its wiper 133 one step, to the first contact of its associated bank. When the wiper 133 of the sequence switch SS is advanced to the first bank contact relay 109 is

energized from ground, contacts 132 of off-normal springs ON, winding of relay 109, to battery. Upon energizing, relay 109 prepares a circuit for the release magnet 117 of the sequence switch SS at armature 135 and its front contact, opens the circuit over conductor 158 to the rotary magnet 116 at armature 136 and its resting contact, opens the cut-in circuit over conductor 42 at armature 134 and its resting contact, and at armature 134 and its front contact prepares a locking circuit over conductor 153 for relay 230. Referring again to pick-up relay 201, it will be noted that at armature 302 and its front contact it prepares a locking circuit for itself in series with relay 202. Interrupter relay 103 subsequently energizes, as has been hereinbefore described, and at armature 122 and its resting contact opens the initial energizing circuit for pick-up relay 201. However, pick-up relay 201 locks up in series with relay 202, as soon as its original energizing circuit is opened, from battery winding of relay 202, to grounded conductor 159. Upon energizing, relay 202 prepares a circuit for counting relay 203 at armature 250 and its front contact.

Interrupter relay 103 subsequently deenergizes again and closes a circuit from grounded conductor 159, armature 252 and its resting contact, contacts 1 and 2 of the striking speed terminal block, armature 138 and its resting contact, armature 141 and its resting contact, conductor 157, armature 250 and its front contact, armature 251 and its resting contact, winding of counting relay 203, to battery. Upon energizing, counting relay 203 prepares a circuit for itself in series with relay 204 at armature 303 and its front contact, and at armature 257 and its front contact closes a circuit from grounded conductor 159, armature 332 and its resting contact, armature 278 and its front contact, armature 257 and its resting contact, conductor 160, armature 142 and its resting contact, armature 139 and its resting contact, terminal G multiplied with terminals E and F and connected to terminal A of terminal block TB1, conductor 62, winding of solenoid 53 of the 120 hours gong C1, to battery. The operation of the solenoid 53 causes the plunger 54 to strike the tuned bar of steel 56. The transmitter 57 fastened to the resonance chamber 56, picks up the chime emitted by the tuned bar 55, when it is sharply struck by the plunger 54, and transmits it over conductors 40 and 40, primary and secondary windings of the transformer 39, to the subscriber at substation T.

Interrupter relay 103 is subsequently energized again and opens the initial energizing circuit over conductor 157 for counting relay 203 at armature 122 and its resting contact. Counting relays 203 and 204 are immediately energized in series from battery, winding of relay 203, armature 303 and its front contact, winding of relay 204, to grounded conductor 159. Upon energizing, counting relay 204 opens the circuit over conductor 160 to the hours gong C1 at armature 279 and its resting contact, it prepares a circuit for counting relay 205 at armature 251 and its front contact, and at armature 264 and its front contact closes a circuit over test conductor 316 for stop relay 113. The circuit for the stop relay 113 is completed at this time from ground, armature 140 and its resting contact, armature 137 and its resting contact, conductor 154, wiper 237 of the hours register HR and its associated first bank contact, test conductor 316, armature 264 and its front contact, conductor 161, winding

of stop relay 113, to battery. Upon energizing, stop relay 113 closes an obvious locking circuit for itself at armature 147, closes a circuit for relay 114 at armature 148 and its front contact, 5 and at armature 149 and its resting contact removes the holding ground from conductor 159 and the armature springs 122, 126, and 130 of the interrupter relays. Due to the removal of holding ground from conductor 159, relays 201—204 of 10 the counting chain immediately restores to normal and due to the removal of ground from the armatures 122, 126, and 130 of the interrupter relays the relays of the counting chain cannot be operated again over conductor 157 until the 15 ground is again restored to these armatures.

By referring again to the operation of stop relay 113, it will be noted that at armature 149 and its front contact it closes a circuit from ground, armature 149 and its front contact, armature 145 and its resting contact, winding of rotary magnet 116, to battery. Upon energizing, rotary magnet 116 advances its wiper 133 to the second contact of its associated bank and closes an obvious circuit for sequence relay 110. Upon energizing, sequence relay 110 removes the ground, over armature 140 and its resting contact, from conductor 154 and the wiper 237 of the hours register HR and connects it to conductor 155 and the wiper 240 of the tens of minutes 25 register TR at armature 137 and its front contact, disconnects the interrupter circuit over armature 122 at armature 138 and its resting contact and connects the interrupter circuit over armature 126 at armature 138 and its front contact, and disconnects the circuit for the hours 30 gong C1 at armatures 139, 166 and 168 and their respective resting contacts and prepares the circuit for the tens of minutes gong C2 at armatures 139, 166, and 168 and their respective front contacts. 35

By referring again to the delay relay 114, which is energized following the energization of the stop relay 113, it will be noted that when it pulls its armature 150 in contact with the weighted 45 spring 151 the weighted spring 151 vibrates and when it comes to rest closes an obvious circuit for the slow-acting relay 115 which subsequently energizes. Upon energizing, relay 115 opens the locking circuit for the stop relay 113 which immediately falls back. Upon falling back, stop relay 113 opens the obvious circuit for relay 114 and it in turn opens the circuit for slow-acting relay 115.

The subscriber has now heard one chime from 55 the hours gong C1 and the apparatus is now in position to transmit the chimes from the tens of minutes gong C2.

When the stop relay 113 deenergizes it replaces the holding ground on conductor 159 and the interrupter armatures 122, 126, and 130 of the interrupter relays. If the interrupter relay 106 is deenergized when ground is replaced on conductor 159 a circuit is immediately closed to the pick-up relay 201 from grounded conductor 159, armature 126 and its resting contact, contacts 3 and 4 of the striking speed terminal block, armature 138 and its front contact, armature 141 and its resting contact, conductor 157, armature 230 and its resting contact, winding of the pick-up relay 201, to battery. Upon energizing, pick-up relay 201 prepares a circuit for relay 202 at armature 302 and its front contact, and at armature 276 and its front contact grounds conductor 158. The grounding of conductor 158 has no effect at this time because the

circuit is opened at armature 136 by the operation of the relay 109 which was energized when the sequence switch SS stepped its wiper 133 off-normal.

Interrupter relay 106 is subsequently energized 80 as has been hereinbefore described, and opens the initial energizing circuit for pick-up relay 201 at armature 126 and its resting contact. However, pick-up relay 201 is immediately energized in series with relay 202, from battery, winding of pick-up relay 201, armature 302 and its front contact, winding of relay 202, to grounded conductor 159. Upon energizing relay 202 prepares a circuit for counting relay 203 at armature 250 and its front contact.

Interrupter relay 106 subsequently deenergizes 85 again and at armature 126 and its resting contact, closes a circuit for counting relay 203 over conductor 157, armature 250 and its front contact, armature 251 and its resting contact, winding of counting relay 203, to battery. Counting relay 203 upon energizing prepares a circuit for counting relay 204 at armature 303 and its front contact, and at armature 278 and its front contact closes a circuit from grounded conductor 159, armature 332 and its resting contact, armature 278 and its front contact, armature 279 and its resting contact, conductor 160, armature 142 and its resting contact, armature 139 and its front contact, terminal J multiplied with terminals H and I and connected to terminal B of terminal block TB1, conductor 61, winding of the solenoid of the tens of minutes gong C2, to battery. The energization of the solenoid of the tens of minutes gong 100 C2 causes its plunger to strike the tuned bar of steel and the chime emitted therefrom is picked-up by the associated transmitter and resonance chamber, and transmitted over conductors 40—41 and the transformer 39 to the subscriber at substation T.

Interrupter relay 106 subsequently energizes 105 again and opens the initial energizing circuit for counting relay 203 at armature 126 and its resting contact. However, counting relay 203 immediately energizes in series with counting relay 204 from battery, winding of counting relay 203, armature 303 and its front contact, winding of counting relay 204, to grounded conductor 159. Upon energizing, counting relay 204 opens the circuit over conductor 160 to the tens of minutes gong C2 at armature 279 and its resting contact, 110 prepares the energizing circuit for counting relay 205 at armature 251 and its front contact, and at armature 264 and its front contact closes a testing circuit for stop relay 113, from test conductor 316, armature 264 and its front contact, conductor 161, winding of stop relay 113, to battery. Due to the fact that the test conductor 316 has not been grounded by any of the wipers of 115 the registers, stop relay 113 is not energized.

Interrupter relay 106 subsequently deenergizes 120 again, and at armature 126 and its resting contact closes a circuit over conductor 157, armature 250 and its front contact, armature 251 and its resting contact, armature 252 and its resting contact, winding of counting relay 205, to battery. Upon energizing, counting relay 205 prepares a locking circuit for itself in series with counting relay 206 at armature 304 and its front contact, 125 and at armature 280 and its front contact closes a circuit from grounded conductor 159, armature 332 and its resting contact, armature 280 and its front contact, armature 281 and its resting contact, conductor 163, armature 165 and its resting contact, armature 166 and its front contact,

terminal I multiplied with terminal H and J and connected to terminal B of the terminal block TB1, conductor 61, winding of the solenoid of the tens of minutes gong C2, to battery. The second chime from the tens of minutes gong C2 is then transmitted as before to the subscriber at substation T.

Interrupter relay 106 is subsequently energized again and the initial energizing circuit for counting relay 205 is opened at armature 126 and its resting contact. However, counting relay 205 immediately locks up in series with counting relay 206 from battery, winding of counting relay 205, armature 304 and its front contact, winding of counting relay 206, to grounded conductor 159. Upon energizing, counting relay 206 prepares a circuit for counting relay 207 at armature 252 and its front contact, opens the circuit over conductor 163 to the tens of minutes gong C2 at armature 281 and its resting contact, and at armature 265 and its front contact closes a circuit from test conductor 317, armature 265 and its front contact, conductor 161, winding of stop relay 113, to battery. Stop relay 113, however, is not energized over this circuit because the test conductor 317 is not grounded by any of the wipers of the registers.

Interrupter relay 106 subsequently deenergizes again and closes a circuit at armature 126 and its resting contact, over conductor 157, armatures 250, 251, and 252 and their respective front contacts, armature 253 and its resting contact, winding of counting relay 207, to battery. Upon energizing, counting relay 207 prepares a locking circuit for itself in series with counting relay 208 at armature 305 and its front contact, and at armature 282 and its front contact it closes a circuit from grounded conductor 159, armature 332 and its resting contact, armature 282 and its front contact, armature 283 and its resting contact, conductor 164, armature 167 and its resting contact, armature 168 and its front contact, terminal H multiplied with terminals I and J and connected to terminal B of the terminal block TB1, conductor 61, winding of the solenoid of the tens of minutes gong C2 to battery. The third chime from the tens of minutes gong C2 is then transmitted over the previously traced circuit to the subscriber at substation T.

Interrupter relay 106 subsequently energizes again and opens the circuit for counting relay 207 at armature 126 and its resting contact. However, counting relay 207 immediately energizes in series with counting relay 208, from battery, winding of relay 207, armature 305 and its front contact, winding of relay 208, to grounded conductor 159. Upon energizing, counting relay 208 opens the circuit for the tens of minutes gong C2 at armature 283 and its resting contact, prepares a circuit for counting relay 209 at armature 253 and its front contact, and closes a circuit at armature 266 and its front contact, from test conductor 318, armature 266 and its front contact, conductor 161, winding of stop relay 113, to battery. Stop relay 113, however, is not energized at this time because test conductor 318 has not been grounded by any of the wipers of the registers.

Interrupter relay 106 subsequently deenergizes again and closes a circuit at armature 126 and its resting contact, over conductor 157, armatures 250—253 and their respective front contacts, armature 254 and its resting contact, winding of counting relay 209, to battery. Counting relay 209 energizes over this circuit and prepares a

circuit for counting relay 210 at armature 306 and its front contact, and at armature 284 and its front contact closes a circuit from grounded conductor 159, armature 332 and its resting contact, armature 284 and its front contact, armature 285 and its resting contact, conductor 160, over the previously traced circuit to the tens of minutes gong C2. The fourth chime from the tens of minutes gong C2 is now transmitted over the previously traced circuit to the subscriber at substation T.

Interrupter relay 106 subsequently energizes again and opens the circuit for counting relay 209 over conductor 157 at armature 126 and its resting contact. However, counting relay 209 immediately energizes in series with counting relay 210 from battery, winding of counting relay 209, armature 306 and its front contact, winding of counting relay 210, to grounded conductor 159.

Upon energizing, counting relay 210 opens the circuit for the tens of minutes gong C2 at armature 285 and its resting contact, prepares a circuit for counting relay 211 at armature 254 and its front contact, and at armature 267 and its front contact closes a circuit from test conductor 319 to stop relay 113. This time the stop relay 113 is energized because the test conductor 319 is grounded by wiper 240 of the tens of minutes register TR. The circuit for energizing the stop relay is as follows: battery, winding of stop relay 113, conductor 161, armature 267 and its front contact, test conductor 319, wiper 240 and the associated fourth bank contact of the tens of minutes register TR, conductor 155, armature 137 and its front contact, armature 140 and its resting contact, to ground. Upon energizing, stop relay 113 closes an obvious locking circuit for itself at armature 147, closes a circuit for relay 114 at armature 148 and its front contact, and at armature 149 and its resting contact removes the holding ground from conductor 159 and the armature springs 122, 126, and 130 of the interrupter relays. By removing the holding ground from conductor 159, relays 201—210 of the counting chain immediately restore to normal, and by removing the ground from armatures 122, 126, and 130 of the interrupter relays the relays of the counting chain cannot be operated again over conductor 157 until the ground is again restored to these armature springs.

By referring again to the operation of stop relay 113, it will be noted that at armature 149 and its front contact it closes a circuit from ground, armature 149 and its front contact, armature 145 and its resting contact, winding of rotary magnet 116, to battery. The rotary magnet 116, upon energizing, advances its wiper 133 to the third contact of its associated bank, and closes an obvious circuit for sequence relay 111. Upon energizing, sequence relay 111 removes the ground over armature 140 and its resting contact from conductor 155 and wiper 240 of the tens of minutes register TR and connects it to conductor 156 and the wiper 243 of the units of minutes register UR at armature 140 and its front contact. Sequence relay 111 also connects up armature 130 of the interrupter relay at armature 141 and its front contact and by the same action disconnects the armature 126 of the interrupter relay at armature 141 and its resting contact, and at armatures 165 and 157 and their respective front contacts prepares a circuit for the units of minutes gong C3 and by the same action at their respective resting contacts it dis-

connects the circuit for the tens of minutes gong C2.

Referring again to the delay relay 114 which is energized following the energization of the 5 stop relay 113, it will be noted that when it pulls its armature 150 in contact with the weighted spring 151 that the weighted spring 151 vibrates and when it comes to rest closes an obvious circuit for the slow-acting relay 115 which subsequently energizes. Upon energizing, relay 115 10 opens the locking circuit for stop relay 113 at armature 152 and its resting contact, and the stop relay 113 immediately falls back. Upon falling back, stop relay 113 opens the obvious circuit for relay 114 and it in turn opens the circuit for the slow-acting relay 115.

The subscriber at substation T has now heard one chime from the hours gong C1 and four chimes from the tens of minutes gong C2. The 20 apparatus is now in the position to transmit the chimes from the units of minutes gong C3.

When the stop relay 113 deenergizes it replaces the holding ground on conductor 159 and the interrupter armatures 122, 126, and 130 of the interrupter relays. When the interrupter relay 108 deenergizes a circuit is closed from grounded conductor 159, armature 130 and its resting contact, contacts 5 and 6 of the striking speed terminal block, armature 141 and its front contact, 25 conductor 157, armature 250 and its resting contact, winding of pick-up relay 201 to battery. Upon energizing, pick-up relay 201 prepares a circuit for relay 202 at armature 302 and its front contact, and at armature 276 and its front contact connects ground to conductor 158. The 30 grounding of conductor 158 has no effect at this time because the circuit over this conductor is open at armature 136 and its resting contact.

Interrupter relay 108 is subsequently energized 40 as has been hereinbefore described, and opens the initial energizing circuit for the pick-up relay 201 at armature 130 and its resting contact. However, pick-up relay 201 is immediately locked up in series with relay 202, from battery, winding of 45 pick-up relay 201, armature 302 and its front contact, winding of relay 202 to grounded conductor 159. Upon energizing relay 202 prepares a circuit for counting relay 203 at armature 250 and its front contact.

Interrupter relay 108 subsequently deenergizes again and at armature 130 and its resting contact, closes a circuit for counting relay 203 over conductor 157, armature 250 and its front contact, armature 251 and its resting contact, winding of 55 counting relay 203 to battery. Upon energizing, counting relay 203 prepares a circuit for counting relay 204 at armature 303 and its front contact, and armature 278 and its front contact closes a circuit from grounded conductor 159, armature 60 332 and its resting contact, armature 278 and its front contact, armature 279 and its resting contact, conductor 160, armature 142 and its front contact, terminal M multiplied to terminals L and K and connected to terminal C of the terminal block TB1, conductor 60, winding of the solenoid of the units of minutes gong C3, to battery. The energization of the solenoid of the units of minutes gong C3 causes its plunger to strike the tuned bar of steel and the chime emitted therefrom is 65 picked up by the associated transmitter and resonance chamber, and transmitted over previously traced circuit to the subscriber at substation T.

Interrupter relay 108 subsequently energizes 70 and opens the initial energizing circuit over con-

ductor 157 for counting relay 203 at armature 130 and its resting contact. Counting relay 203 is immediately energized in series with counting relay 204 from battery, winding of counting relay 203, armature 303 and its front contact, winding of counting relay 204, to grounded conductor 159. Upon energizing, counting relay 204 80 opens the circuit over conductor 160 to the units of minutes gong C3 at armature 279 and its resting contact, prepares a circuit for counting relay 205 at armature 251 and its front contact, closes a circuit over test conductor 316 to stop relay 113 at armature 264 and its front contact. The circuit for the stop relay 113 is completed 85 at this time from ground, armature 140 and its front contact, conductor 156, wiper 243 and the first bank contact of the units of minutes register UR, test conductor 316, armature 264 and its front contact, conductor 161, winding of stop relay 113, to battery. Upon energizing, stop relay 113 closes an obvious locking circuit for itself 90 at armature 147, closes a circuit for relay 114 at armature 148 and its front contact, and at armature 149 and its resting contact removes the holding ground from conductor 159 and the 95 armature springs 122, 126, and 130 of the interrupter relays. By removing the holding ground from conductor 159, relays 201—204 of the counting chain immediately restore to normal and by removing the ground from armatures 122, 126, and 130 of the interrupter relays, the relays of the counting chain cannot be operated again 100 over conductor 157 until the ground is again restored to these armatures.

By referring again to the operation of stop relay 113, it will be noted that armature 149 and its front contact closes a circuit from ground, armature 149 and its front contact, armature 145 and its resting contact, winding of rotary magnet 116, to battery. Upon energizing, rotary magnet 116 advances its wiper 133 to the fourth bank contact of its associated bank, and closes an obvious circuit for sequence relay 112. Upon energizing, relay 112 closes an obvious locking 110 circuit for itself from ground at armature 149 and its front contact, opens the circuit for the rotary magnet 116 at armature 145 and its resting contact, and at armature 145 and its front contact closes an obvious circuit for release magnet 117 of the sequence switch SS. Due to the 115 operation of the release magnet 117 the wipers 133 of the sequence switch SS immediately restore to normal and opens the off-normal contacts 132. Due to the opening of contacts 132 the circuit of relay 109 is opened and it subsequently restores 120 to its normal position.

By referring again to the delay relay 114, which is energized following the energization of the stop relay 113, it will be noted that when it pulls its armature 150 in contact with the weighted spring 151 that the weighted spring 151 vibrates and when it comes to rest closes an obvious circuit for the slow-acting relay 115, which subsequently energizes. Upon energizing, relay 115 125 opens the locking circuit for the stop relay 113 which immediately falls back. Upon falling back stop relay 113 opens the obvious circuit of relay 114 and it in turn opens the circuit for slow-acting relay 115.

By referring again to the stop relay 113 it 135 will be noted that when this falls back the locking circuit for relay 112 is opened at armature 149 and its front contact. However, relay 112 is slow-to-release and does not fall back for a short time. At armature 149 and its resting 140

145

150

contact stop relay 113 closes a circuit from ground, armature 149 and its resting contact, armature 146 and its front contact, conductor 44, armature 37 and its front contact, armature 28 and its resting contact, winding of relay 19, to battery. Upon energizing, relay 19 prepares a locking circuit for itself in series with relay 20 at armature 27 and its front contact. Relay 20 is short-circuited for the time being by the 5 initial circuit for relay 19 over conductor 44. The slow-to-release relay 112 subsequently falls back and opens the initial energizing circuit for relay 19 at armature 146 and its front contact. As soon as its initial energizing circuit is opened 10 relay 19 locks up in series with relay 20 from battery, winding of relay 19, armature 27 and its front contact, winding of relay 20, armature 26 and its front contact, to ground. Upon energizing, relay 20 prepares a circuit for the kick-off 15 relay 21 at armature 28 and its front contact.

The subscriber at substation T has now heard one chime from the hours gong C1, four chimes from the tens of minutes gong C2, and one chime from the units of minutes gong C3, indicating 20 that the time is 1:41 o'clock. The time signaling device is now in position to transmit the same time signal to the subscriber again, and the holding-bridge circuit HB is in position to disconnect the subscriber from the time signaling device and 25 connect him to the busy-tone conductor after he has received the time signal again.

It should be noted that the pick-up circuit over conductor 42 is closed at this time and will connect any subscriber that has seized a holding-bridge circuit similar to holding-bridge circuit HB to the time signaling conductors 40 and 41 over the transformer associated with his holding-bridge circuit. A holding-bridge circuit cannot be connected to the time signaling conductors after the transmission of a time signal has started, because the pick-up circuit over conductor 42 will be opened at armature 134 and its resting contact.

The operation of the time signaling device when 30 transmitting the second time signal to the subscriber connected to holding-bridge circuit HB is the same as has been hereinbefore described. However, after the last signal has been transmitted, the stop relay 113 falls back and opens the circuit for the slow-to-release relay 112. With the stop relay deenergized and the slow-to-release relay still in its operated position a circuit is closed from ground, armature 149 and its resting contact, armature 146 and its front contact, conductor 44, armature 37 and its front contact, armature 28 and its front contact, lower winding of kick-off relay 21, to battery. Upon energizing, kick-off relay 21 locks itself over its upper winding from battery, upper winding of kick-off relay 21, armature 33 and its front contact, armature 26 and its front contact, to ground. At armatures 29 and 34 and their respective resting contacts, relay 21 disconnects the subscriber 35 from the time signaling conductors, opens the circuit for the switch-through relay 22 at armature 32 and its resting contact, and at armature 30 and its resting contact opens the circuit for the start relay 102 of the time signaling device. At armature 34 and its front contact, relay 21 connects the subscriber to the busy-tone transformer 52.

Ordinarily the subscriber will hang up his receiver after he has heard the complete time signal the first time. If he is uncertain as to what

time was transmitted he may listen to the next complete time signal. However, it is undesirable to permit the subscriber to listen to the time signal indefinitely, and therefore, the equipment is arranged to connect him to the busy signaling conductor after he has heard the second complete time signal. In this way the trunks of the signaling device are not tied up any longer than necessary.

Upon hearing the busy-tone the subscriber will hang up his receiver and in so doing opens the loop circuit for the line relay 17 of the holding-bridge circuit HB. Upon deenergizing, line relay 17 opens an obvious circuit to release relay 18. Relay 18 subsequently deenergizes and at armature 26 and its front contact removes the holding ground from conductor 15 and the preceding switches restore to normal in the usual manner. The removal of ground at armature 26 and its front contact causes relays 19, 20, and 21 to restore to normal. The holding-bridge circuit HB is now in position to be seized again by any subscriber having access to the time signaling device.

The impedance coil 64 and the condenser 65, 100 of the holding-bridge circuit HB, constitute a tuned circuit which permits the sound of the gongs to be received by the subscriber perfectly, but effectively prevents two or more subscribers from talking to each other while listening to the 105 time signaling device.

Automatic subscriber seizing a holding-bridge circuit after the time signaling device has started transmitting a time signal to another connected subscriber

It will be assumed that the time signaling device has started transmitting the time signal over conductors 40 and 41 to a subscriber connected to a holding-bridge circuit, similar to holding bridge HB, and that a second subscriber seizes the holding-bridge circuit HB after the first two digits of the signal have been transmitted by the hours and tens of minutes gong C1 and C2, respectively.

Line relay 17 of the holding-bridge circuit HB energizes over the subscriber's loop circuit as before. Line relay 17 closes an obvious circuit for the release relay 18. At armature 26 and its front contact, release relay 18 grounds the release trunk conductor 15 to hold the selector and preceding switches operated. At armature 24 and its front contact, relay 18 prepares a pick-up circuit for relay 22. The circuit for pick-up relay 22 over conductor 42 has been opened by relay 109 at armature 134 and its resting contact. It will be remembered that relay 109 operates as soon as the sequence switch SS advances its wiper 133 from its normal position. Therefore, the second subscriber desiring to be connected to the time signaling device must wait until the time signal being transmitted to the first subscriber has been completed and relays 109 and 112 are restored to their normal positions. At armature 25 and its front contact, release relay 18 grounds the start conductor 43 to maintain the start relay 102 of the time signaling device in an operated position after the first subscriber disconnects.

With the pick-up relay 22 in its normal position, the subscriber connected to the holding-bridge circuit HB will receive a tick-tock tone signal similar to the ticking of a grandfather clock. The circuit for the tick-tock tone is completed by the operation of the interrupter relays

80

150

103 and 104. With the interrupter relay 104 in its normal position, a circuit can be traced from battery, lower winding of relay 104, conductor 59, one winding of transformer 49, condenser and ground. However, relay 104 does not operate over this circuit. When relay 104 is energized as described hereinbefore and locked to ground at conductor 58, the circuit over conductor 59 to transformer 49 is short-circuited. This breaking and making of the circuit through the winding of transformer 49 causes a tone signal, similar to the ticking of a clock, to be transmitted over conductors 45 and 46, armatures 35 and 38 and their respective resting contacts, armatures 29 and 34 and their respective resting contacts, to the subscriber connected to the holding-bridge circuit HB. The tick-tock tone signal indicates to the subscriber that a connection has been established for the time signaling device. After the time signal, being transmitted by the signaling device to the first subscriber, is completed, relays 109 and 112 of the time signaling device will restore to normal and close a circuit to the pick-up relay 22 of the holding-bridge circuit HB, from ground, armature 143 and its resting contact, armature 134 and its resting contact, conductor 42, armature 24 and its front contact, lower winding of switch-through relay 22, armature 32 and its resting contact, resistance 31, to battery. Switch-through relay 22 locks up over its upper winding as before, and at armatures 35 and 38 and their respective resting contacts opens a circuit to the tick-tock tone conductors 45 and 46 and connects the subscriber to the time signaling conductors over the transformer 39 at armatures 35 and 38 and their respective front contacts. The transmission of the time signals and the connecting of the busy-tone to the subscriber's line after he has heard the complete time signal transmitted twice is exactly the same as has been described hereinbefore.

Transmission of special signal when the wipers of the tens of minutes register TR are associated with the sixth bank contact and the wipers of the units of minutes register UR are associated with the tenth bank contact

It will be assumed that the wipers of the tens of minutes register TR are associated with the sixth bank contact, that the wipers of the units of minutes register UR are associated with the tenth bank contact, and that the signaling device has transmitted the time registered on the hours register HR, as has been hereinbefore described.

After the time registered on the hours register HR has been transmitted by the hours gong C1, the stop relay 113 is energized, as has been pointed out. Upon energizing, the stop relay 113 removes the holding ground from conductor 159 to allow the counting relays to fall back and also to remove the ground from armatures 122, 126, and 130, so that the operation of the interrupter relays 101-108 has no effect at this time. At armature 149 and its front contact, stop relay 113 closes a circuit for rotary magnet 116 of the sequence switch SS. Whereupon wiper 133 is advanced to its associated second bank contact and closes an obvious circuit for sequence relay 110. At the resting contacts of armature 137, relay 110 removes the ground from conductor 154, and at the front contact of armature 137 a circuit is closed from ground, armature 140 and its resting contact, armature 137 and its front contact, conductor 155, wiper 240 of the tens of minutes register TR and its associated sixth bank con-

tact, conductor 315, winding of relay 200, to battery. Relay 200 energizes over this circuit. Relay 110 also opens the circuit to the hours gong C1 at armatures 139, 166, and 168, and their respective resting contacts and at the front contacts of these armatures a circuit is prepared for the tens of minutes gong C2.

By referring again to the operation of relay 200, it will be noted that at armature 332 and its resting contact a circuit is opened so that the operation of the counting relays inclosing the front contacts of armatures 278, 280, 282, and 284 to operate the gongs is not effective as long as relay 200 is operated. At armature 263 and its front contact, relay 200 grounds conductor 331 and test conductor 318 by way of the terminal block TB. It will be noted that by changing the connection on the terminal block TB it is a very simple matter to connect conductor 331 to any one of the test conductors 316, 317, 318, and 319. The length of the tone signal transmitted by buzzer B1 depends on the particular test conductor grounded by armature 263 of relay 200.

The stop relay 113 subsequently deenergizes, as has been hereinbefore described, and replaces the holding ground on conductor 159 and the interrupter armatures 122, 126, and 130 of the interrupter relay. It is believed that the operation of the pick-up relays 201-202 and the counting relays 203-226 is quite clear, and it is not thought necessary to describe the detail operation again. Following the energization of the pick-up relays 201-202, counting relay 203 is subsequently energized, and at armature 277 and its front contact a circuit is closed from ground, armature 330 and its front contact, armature 277 and its front contact, conductor 169, terminal N connected to terminal D of the terminal block TB1, winding of buzzer B1, resistance 170, to battery. The vibration of the buzzer causes a tone signal to be transmitted over conductors 66 and 67, conductors 40 and 41, transformer 39, to the subscriber. The counting relays are successively test conductors 316 to 319 for a marking ground to operate the stop relay 113. However,

if no ground is encountered on these conductors the stop relay is not energized. When counting relay 208 is energized, however, a circuit is closed from ground, armature 263 and its front contact, conductor 331, connected to test conductor 318 by way of the terminal block TB, armature 266 and its front contact, conductor 161, winding of stop relay 113, to battery. At armature 149 and its resting contact, stop relay 113 removes the holding ground from conductor 159 and armatures 122, 126, and 130 of the interrupter relays. By removing the holding ground from conductor 159 all the counting relays in the chain fall back as before. At armature 277 and its front contact, counting relay 203 opens the circuit for the buzzer B1.

Referring again to the operation of stop relay 113, it will be noted that at armature 129 and its front contact it again closes a circuit for the rotary magnet 116 of the sequence switch SS, advancing its wiper 133 to its associated third bank contact. Sequence relay 110 deenergizes as soon as the wiper is stepped off the second bank contact and sequence relay 111 is energized as soon as wiper 133 encounters the third bank contact. As soon as sequence relay 110 falls back, it removes the ground from conductor 155, allowing relay 200 to restore to normal. At armature 140 and its front contact, sequence relay 111

closes a circuit from ground, armature 140 and its front contact, conductor 156, wiper 243, and the associated tenth bank contact of the units of minutes register UR, conductor 315, winding of relay 200, to battery. Relay 200 energizes as before to prepare the circuit for the buzzer B1. The operation of the equipment with wiper 243 of the units of minutes register UR resting on its associated tenth bank contact is exactly the same as described above. With the arrangement provided above, the subscriber receives a long continuous tone signal to indicate 0 or zero, instead of transmitting ten chimes from any particular gong, or just providing a silent period.

15 The time transmitted with the registers in the position described above is 1:00 o'clock.

Setting of the registers by the master clock

The setting of the hours register HR, the tens of minutes register TR, and the units of minutes register UR, by momentary impulses from a master clock will now be described. Conductor 328 shown in the upper left-hand corner of Fig. 3 is connected to a master clock that is arranged to momentarily close a pair of contacts once every minute. Every time the clock operates its contacts a ground pulse is transmitted over conductor 328, upper winding of relay 230, to battery. It will be assumed that no subscribers are connected to the time signaling device and that of the relays, therefore, are in the position shown on the drawings. Relay 230 is only momentarily energized by each ground pulse from the master clock over conductor 328 and is not locked up over its lower winding over conductor 153 because the circuit over conductor 153 is opened at armature 134 and its front contact. At armature 235 and its front contact, relay 230 closes an obvious circuit to magnet 231 of the units of minutes register UR. Magnet 231 energizes but is arranged to advance its wipers 241, 242, and 243 when it is deenergized. Relay 230 is only momentarily energized and subsequently falls back and opens a circuit for magnet 231. Magnet 231 deenergizes and advances its wipers 241-243 to the next bank contact. It is obvious then that each time relay 230 is momentarily operated, magnet 231 of the units of minutes register UR advances its wipers step-by-step over their associated bank contacts.

50 When the wipers 241-243 of the units of minutes register UR are advanced to the ninth bank contact a circuit is closed from ground, wiper 241 and its associated ninth bank contact, winding of the magnet 232 of the tens of minutes register TR, to battery. The tens of minutes register magnet 232 energizes, and when the wiper 241 of the units of minutes register UR is advanced to the tenth bank contact the circuit to magnet 232 is opened. The deenergization of magnet 232 causes its wipers 238-240 to be advanced one step. Each time the magnet 231 of the units of minutes register UR advances its wipers to the ninth bank contact the circuit is closed to magnet 232 of the tens of minutes register TR, and when the wipers of the units of minutes register UR are advanced to the tenth bank contact the circuit is opened and the wipers of the tens of minutes register TR are advanced another step. Each time the wiper 242 of the units of minutes register UR is advanced to its ninth bank contact with the wiper 239 of the tens of minutes register TR resting on its fifth bank contact a circuit is closed from ground, wiper 242 and its associated ninth bank contact, wiper 239 and its associated fifth bank contact,

armature 244 and its resting contact, winding of the magnet 233 of the hours register HR, to battery. When the units of minutes register UR steps its wipers off the ninth bank contact the circuit for the hours magnet 233 is opened at 80 wiper 242. Therefore, each time the wiper 242 and wiper 239 of the units of minutes register and the tens of minutes register, respectively, are associated with their respective ninth and fifth bank contacts the circuit is closed for magnet 85 233 of the hours register, and each time these wipers are stepped off these respective contacts the circuit to the hours register is opened and it advances its wipers 236-237 one step.

90 When the magnet 233 of the hours register HR advances its wipers 236-237 to the eleventh bank contact a circuit is closed from ground, wiper 236 and its associated eleventh bank contact, winding of relay 227 to battery. Therefore, the next time wipers 242 and 239 are associated with their respective ninth and fifth bank contacts a circuit is closed from ground, wiper 242 and its ninth bank contact, wiper 239 and its fifth bank contact, armature 244 and its front contact, armature 247 and its resting contact, 100 winding of relay 228 to battery.

95 Referring again to the operation of relay 227 when the wipers of the hours register is associated with its eleventh bank contact. A circuit is closed from ground, armature 245 and its front 105 contact, armature 249 and its resting contact, to test conductor 326. Therefore, when relay 227 is operated and closes a ground circuit at armature 244, the hours register will be marking 11:00 o'clock, and when the circuit is closed over wipers 110 242 and 239 to relay 228, relay 228 prepares a circuit at armature 246 in series with relay 229, from ground at wiper 236 and its associated eleventh bank contact. Therefore, when wipers 242 and 239 are stepped to their next bank contact the circuit to relay 228 is opened, however, relay 228 immediately energizes in series with relay 229 from battery, winding of relay 228, armature 246 and its front contact, winding of relay 229 to ground at wiper 236 and its associated eleventh bank contact.

115 When relay 229 is energized it prepares a circuit for operating the magnet 233 of the hours register the next time a circuit is closed over wipers 242 and 239, and at armature 249 and 125 its front contact, relay 229 places ground on the test conductor 327, indicating that the time registered is 12:00 o'clock. Next time a circuit is closed over wipers 242 and 239 and their associated ninth and fifth bank contacts the magnet 130 232 of the hours register is operated over a circuit including armature 248 and its front contact. When the wipers 242 and 239 are advanced to their next bank contacts the magnet 233 of the hours register is deenergized and advances its 135 wipers 236-237 to its first bank contact. In advancing its wiper 236 the magnet 233 opens a circuit to the relays 227, 228, and 229 and they immediately fall back to their normal position.

140 It can be plainly seen that each minute the wipers of the units of minutes register UR are advanced one step, every ten minutes the wipers of the tens of minutes register TR advance one step, and each hour the wipers of the hour register HR advance one step until its wipers are associated with the eleventh bank contact, at which time a circuit is completed to relay 227 for marking 11:00 o'clock, which in turn prepares a circuit for relays 228 and 229 to mark 12:00 o'clock.

145 It will be noted that magnets 231 and 232 are 150

provided with self interrupting contacts. This provision is made so that when the units of minutes register advances its wipers to its eleventh bank contact the self interrupting circuit is closed from ground at wiper 241, eleventh bank contact, self interrupting contact and winding of magnet 231, to battery. This immediately steps wipers 231, 242, and 243 to the first bank contact again. When the wipers 238, 239, and 240 of the tens of minutes register are associated with the seventh bank contact a self-interrupting circuit is closed for magnet 232 from ground at wiper 238, and as the seventh, eighth, ninth, tenth, and eleventh bank contacts are all strapped together, the magnet will be operated in a buzzer-like-manner until the wipers 238, 239, and 240 are again associated with the first bank contact.

The bank of the lamps shown to the right of Fig. 3 are lighted to display the exact time registered on the time signaling device at any time of the day. It will be noted that the bank contacts 1 to 10, of the units of minutes register UR, associated with wiper 241 are wired to the units of minutes lamps 1 to 9 and 0, respectively. When the wiper 241 advances from one bank contact to the next the lamp connected with the bank contact to which the wiper is associated will be lighted. The bank contacts 1 to 6 associated with wiper 238 of the tens of minutes register TR are wired to the tens of minutes lamps 1 to 5 and 0. When the wiper 238 advances from one bank contact to the next, the lamp wired to the associated bank contact will be lighted, indicating that the time is ten, twenty, thirty, forty, fifty minutes after the hour or exactly on the hour. The bank contacts 1 to 10 associated with wiper 236 of the hours register HR are wired to the hours lamps 1 to 10, inclusive. As the wiper 236 is then advanced from one bank contact to the next the lamp associated with that contact is lighted, indicating the exact hour. However, when the wiper 236 is associated with the eleventh bank contact it will be remembered that relay 227 is energized and a circuit is closed from ground, armature 245 and its front contact, armature 249 and its resting contact, to the lamp indicating 11:00 o'clock. It will be remembered that relays 228 and 229 are energized in series when the time register is 12:00 o'clock. A circuit is closed from ground, armature 245 and its front contact, armature 249 and its front contact, to the lamp indicating 12:00 o'clock. The lamp 329 is provided to indicate, to the wire chief or other persons responsible for the supervision of the equipment, that the time signaling device has been seized by a subscriber and is transmitting a time signal. When the sequence switch SS is stepped off-normal a circuit is closed from ground, off-normal contacts 132 of the sequence switch, conductor 162, lamp 329 to battery. Therefore, the lamp 329 will be lighted as soon as the sequence switch is stepped off-normal and will be dark when the sequence switch is in its normal position.

When the wipers 241, 238, and 236 of the register in the position shown on the drawings the hours lamp designated is lighted, the tens of minutes lamp designated 4 is lighted, and the units of minutes lamp designated 1 is lighted, indicating that the time registered is 1:41 o'clock.

Change in time while the subscriber is receiving a time signal

It will be assumed that a subscriber is connected to a time signaling device and that he is

receiving the time signals transmitted over conductors 40 and 41 and the transformer 39.

If relay 230 is operated by ground pulse over conductor 328 from a master clock it will immediately lock up over a circuit from battery, lower winding of relay 230, armature 234 and its front contact, conductor 153, armature 134 and its front contact, armature 143 and its resting contact to ground. As long as relay 109 is energized and relay 112 is deenergized, relay 230 will remain locked up over this circuit. At armature 235 and its front contact, relay 230 holds the magnet 231 in an energized position. It will be remembered that as long as the magnet is in energized position the wipers associated therewith are not advanced. The relay 230 is held up over this circuit so that the subscriber listening to a time signaling device receives the time that is registered when he is connected to the time signaling device. After the time signal has been transmitted to the connected subscriber relay 112 energizes, as has been hereinbefore described. As soon as relay 112 energizes, the locking circuit for relay 230 is opened at armature 143 and its resting contact. Relay 230 deenergizes and opens the circuit to magnet 231 causing its wipers to advance one step. If the subscriber connected to the time signaling device has only heard one complete time signal and desires to listen to the second complete time signal he receives the new time registered by the operation of relay 230.

Release of the time signal device when the time signal is only partially transmitted

It will be assumed that a subscriber is connected to the time signaling device and has grounded the start conductor 43, and the start relay 102 has energized and locked itself over armature 119 and its front contact to grounded start conductor 43. Relay 102 also closes a circuit over armature 121 and its front contact to relay 101. Relay 101 upon energizing, opens the initial energizing circuit for start relay 102 at armature 118 and its resting contact.

It will be assumed that the hours signal has been received by the subscriber and that the tens of minutes register is partially transmitted, therefore, the sequence switch SS will have its wiper 133 positioned to its third bank contact and relay 111 will be energized, together with relay 109 which is energized as soon as the sequence switch steps off-normal.

If the subscriber hangs up at this time start relay 102 immediately deenergizes and at armature 120 and its resting contact closes a circuit from ground, armature 120 and its resting contact, armature 135 and its front contact, winding of release magnet 117 to battery. At armature 121 and its front contact, start relay 102 opens the circuit to relay 101 and the counting relays over conductor 159. All the counting relays that have been energized and locked up over conductor 159 immediately fall back. Relay 101, however, is a slow-to-release relay and remains energized for a short time. If any other subscriber should ground the start conductor 43 at this time, relay 102 cannot operate to start the time signaling device again. The slow-to-release relay 101 is provided to allow sufficient time for the sequence switch SS to restore to normal after the release magnet 117 is operated, as well as the relays that are operated when the first subscriber hung up his receiver. Relay 101 subsequently deenergizes and the start relay 102 energizes, by the second subscriber, over arma-

ture 118 and its resting contact and grounded conductor 43, and locks up over armature 119 and its front contact to grounded conductor 43.

Changing the striking speed of the chimes

- 5 The striking-speed terminal block shown in Fig. 2 is wired so that the counting relays are operated at three different speeds. The operating speed of the counting relays in turn control 10 the striking of the various chimes. When the chime indicating the hour is being operated, the ground impulses for operating the counting relays are transmitted about forty times a minute and it follows that the connected chime will be 15 struck at the corresponding speed. When the tens of minutes are being transmitted the counting relays are operated by ground impulses transmitted about eighty times a minute and the connected chime is struck at a corresponding speed. 20 When the units of minutes are being transmitted the impulses for operating the counting relays are transmitted about one-hundred and twenty times per minute, and the connected chime is struck at the same speed. 25 It may be desirable in some cases, to have all the chimes striking at the same speed, say about eighty times per minute. It has been pointed out hereinbefore that the operating speed of the counting relays is governed by the interrupter contacts 122, 126, and 130 and that the striking of the chimes is governed by the speed of the operation of the counting relays. In order to have all the chimes striking at the same speed, that is eighty times per minute, whether it is for 30 the hours, tens or units of minutes, the terminals 2, 4, and 6 of the striking speed terminal block shall be strapped together and connected to terminal 3. With the terminal block wired in this manner the interrupter contacts 126, which are operated eighty times per minute, are the only ones used for operating the counting relays. The interrupter contacts 122 and 130 are connected to terminals 1 and 5 of the striking speed terminal block but are not jumped to any of the contacts 45 2, 4, or 6 for operating the counting relays.

Of course, it is not necessary to use this particular arrangement inasmuch as the terminal block provides facilities for cross-connecting to any of the three striking speeds.

50 It is recommended, however, that the scheme shown in the drawings be used, because a subscriber can differentiate between the hours, tens of minutes, and units of minutes chimes, not only by the pitch or tone of the chime but also by the speed at which it is struck.

Changing the connections of the chimes C1, C2, and C3, at terminal block TB1

55 It will be remembered that when the time signaling device is transmitting the hours the transfer relays 110 and 111 are in their normal positions and that the ground impulses for operating the chime C1 are transmitted over conductors 160, 163, and 164, and the resting contacts of the three lower armatures of relays 110 and 111. The resting contacts of the three lower armatures of transfer relay 110 are wired to terminals E, F, and G of the terminal block TB1 and cross-connected to terminal A to connect up the C1 65 chime over conductor 62.

70 When the time signaling device is transmitting the tens of minutes signals the transfer relay 110 is energized, completing the circuit, at the front contacts of its three lower armatures to terminals H, I, and J of the terminal block TB1

and cross-connected to terminal B to connect up the C2 chime over conductor 61.

When the units of minutes are transmitted by the time signaling device, the transfer relay 111 is in its energized position and the front contacts of the three lower armatures are connected to terminals K, L, and M of the terminal block TB1, whereby the C3 chime is connected up over conductor 60 by means of the jumper connecting terminal C to terminals K, L, and M.

80 It is not necessary, however, to have the chimes connected up in this particular manner as will be pointed out hereinafter. The terminal block TB1 is provided as a convenient arrangement for cross-connecting any of the chimes C1, C2, and C3 with the contacts of the two transfer relays 110 and 111.

90 With the present arrangement the C1 or low-pitched chime is used for transmitting the hours signal only; the C2 or medium chime is used to transmit the tens of minutes signal only; and the C3 or high-pitched chime is used to transmit the units of minutes, as has been hereinbefore described. However, it may be desirable in some cases to change the particular arrangement for 100 striking the chimes to facilitate counting the hours as they are struck. One method that is particularly satisfactory is to use all three chimes C1, C2, and C3 when the time signaling device 105 is transmitting the hours, and using the C2 chime for striking the tens of minutes and the C3 chime for striking the units of minutes as before. To make this alteration it is only necessary to remove the jumpers from terminals A, E, F and G to terminal block TB1 and connect three jumpers, one between terminals A and G, the second between terminals B and F, and the third between terminals C and E. The other jumpers on the terminal block remain as is shown in the drawings.

110 With the terminal block TB1 cross-connected as described above the chimes C1, C2, and C3 are struck consecutively and repeated again, depending upon the hour being transmitted. For example if it is three o'clock the first ground 115 pulse operates the low-pitched chime C1, the second pulse operates the medium-pitched chime C2, and the third pulse operates the high-pitched chime C3. When it is five o'clock the three chimes are operated as above pointed out and the fourth pulse operates the low-pitched chime C1 again and the fifth pulse operates the medium-pitched chime C2 again. It can be plainly seen that, if it is three, six, nine or twelve o'clock the low, medium and high-pitched chimes are 120 each struck once for three o'clock, twice for six o'clock, three times for nine o'clock and four times for twelve o'clock, respectively. With the chimes striking in a musical scale low, medium and high-pitched, in consecutive order, the counting of the tone beats as they are transmitted is 125 comparatively a simple matter. The striking of the tens of minutes and the units of minutes chimes C2 and C3 is the same as has been described in connection with the detailed operation of the time signaling device, inasmuch as the jumpers at the terminal block TB1 have not been changed.

130 Other combinations for striking the chimes may be used by merely changing the jumpers on terminal block TB1, but it is not thought necessary to list all the possible combinations in the specification.

135 What is claimed is:

1. In combination, a plurality of registers for 140 registering the time of day, an impulse sender,

- a plurality of counting relays, a start relay, means for operating said start relay to control said impulse sender, and means including said impulse sender and said counting relays for continuously transmitting the time registered by said registers as long as said start relay is operated. 80
2. In a time signaling device, continuously operating registering devices for registering the time of day, a transmitting device, a plurality of chimes, means for starting said transmitting device, and means including said transmitting device for controlling said chimes in sequence to transmit the time registered. 85
15. 3. In a time signaling device, continuously operating registering devices for registering the time of day, a transmitting device, a plurality of chimes, means for starting said transmitting device, and means including said transmitting device for controlling said chimes in sequence to transmit signals indicative of the time registered. 90
20. 4. In a signaling device, a plurality of chimes, a resonance chamber fastened to each of said chimes, a telephone transmitter mounted on each 95 of said resonance chambers, a circuit including said transmitters, means for operating any one of said chimes, and means including the transmitter for transmitting the tone emitted therefrom over said circuit. 100
30. 5. In a signaling device, a plurality of chimes, a resonance chamber fastened to each of said chimes, a transmitter mounted on each of said resonance chambers, a circuit including all of 105 said transmitters, a circuit for each of said chimes, means for completing a circuit to operate any one of said chimes, said transmitter responsive to the operation of any chime to transmit the tone emitted therefrom over the circuit including all of said transmitters. 110
40. 6. In combination, a plurality of transfer relays, a sequence switch for controlling the operation of each of said transfer relays in proper sequence, a plurality of registers arranged to perform successive controlling operations, and means controlled by said transfer relays for making said registers effective to perform said controlling operations in proper sequence. 115
50. 7. In combination, a plurality of transfer relays, a sequence switch for controlling the operation of each of said transfer relays in proper sequence, a plurality of registers arranged to perform successive controlling operations, means controlled by said transfer relay for making said registers effective to perform said controlling operations in proper sequence, an impulse sender, a plurality of counting relays, and means controlled by said impulse sender and said counting relays for operating said sequence switch at predetermined intervals. 120
60. 8. In a time signaling system, a plurality of time registers, clock controlled means for setting said registers, a plurality of striking chimes each having a different tone, a resonance chamber and transmitter associated with each of said striking chimes, and means for operating each of said chimes in accordance with the setting of said registers, respectively. 125
70. 9. In a time signaling system, a plurality of subscribers' stations having access to said system, a plurality of registers, automatic means for setting and resetting said registers in accordance with the time of day, a like plurality of chimes, means for operating said chimes in accordance 130 with the setting of the said registers, respectively, 135
- and means for transmitting the tone signals emitted by said chimes to said subscribers' stations. 140
10. In a time signaling system, a plurality of subscribers' stations, a plurality of registers, automatic means for changing the setting of said registers in accordance with the passage of time, a like plurality of chimes, means for operating said chimes in accordance with the setting of said registers, respectively, and a resonance chamber and transmitter associated with each of said chimes for transmitting the tone, emitted when said chimes are operated, to said subscribers' stations. 145
11. In combination, a plurality of transfer relays, a plurality of time registers, a like plurality of impulse senders each transmitting impulses at a different speed, and means controlled by said transfer relays for connecting said impulse senders to control said registers, respectively. 150
12. In a time signaling device, a plurality of registers for registering the time of day, a display panel visually indicating the time registered by said registers, and a transmitting device transmitting tone signals indicating the time registered by said registers. 155
13. In a time signaling system, a transmitting device for transmitting tone signals indicative of the time of day, a plurality of trunk circuits for connecting subscribers to said transmitting device, a start circuit for said device, and means for maintaining said start circuit closed as long as a subscriber is connected to said transmitting device. 160
14. In a time signaling device arranged to transmit signals indicative of the time of day, means for transmitting signals indicative of the hour at one speed, means for transmitting signals indicative of the group of minutes at a faster speed, and means for transmitting signals indicative of the minute within the group at a still faster speed. 165
15. In combination, a plurality of tone signals, an interrupter for each of said tone signals, each of said interrupters operating at a different predetermined speed, and means for connecting any one of said interrupters to control any one or all of said tone signals. 170
16. In a time signaling system, a plurality of registers for registering the time of day, means for transmitting signals indicative of the time registered on said registers, means for disconnecting said transmitting means when said registers are positioned to predetermined settings, and means for transmitting a special signal indicative of the predetermined settings of said registers. 175
17. In a time signaling system, a plurality of registers for registering the time of day, means for transmitting signals indicative of the time registered on said registers, means for disconnecting said transmitting means when said registers are positioned to predetermined settings, means for transmitting a special signal indicative of the predetermined settings of said registers, and means for varying the duration of said special signal. 180
18. In combination, a plurality of transfer relays, a sequence switch, a plurality of registers arranged to perform successive controlling operations, means for controlling said sequence switch to operate said transfer relays in sequence, means controlled by said transfer relays for making each of said registers effective to perform said controlling operations in proper sequence, and means 185

for restoring said sequence switch to normal after all of said registers have been effective.

19. In a time signaling system, a plurality of impulse senders each transmitting impulses at a different speed, a plurality of registers for registering the time of day, a plurality of chimes, a plurality of counting relays for controlling the operation of said chimes, and means for connecting each of said impulse senders in turn to successively control said counting relays.

20. In a time signaling system, a register for registering the hours, a register for registering the minutes, a chime for each of said registers, means for operating one of said chimes under control of the hours register, means for subsequently operating the other chime under control of the minutes register, and means for connecting said chimes so they are alternately controlled by said hours register and are subsequently alternately controlled by said minutes register.

21. In a time signaling device, a register comprising a step-by-step rotary switch and a plurality of relays, means for progressively operating said rotary switch step-by-step to register certain hours of the day, and means for subsequently progressively operating said relays to register the remaining hours of the day.

22. In a time signaling device, a step-by-step rotary switch, means for progressively operating said rotary switch step-by-step to register certain hours of the day, and a plurality of relays for registering the remaining hours of the day progressively operated after said rotary switch is operated to a predetermined position.

23. In a time signaling system, a plurality of switches for registering the time of day, means for advancing the wipers of said switches to register the time, transmitting apparatus, a calling subscriber, means controlled by said subscriber for causing said apparatus to transmit the time registered, and means responsive when said calling subscriber releases when only a portion of the time registered has been transmitted for restoring the transmitting apparatus to its normal starting position.

24. In a time signaling device, a plurality of switches for registering the time of day, means for giving them a continuous forward step-by-step movement, means for transmitting tone signals indicative of the time registered on said switches, a sequence switch, means for advancing said sequence switch one step each time the time registered on one of said switches has been transmitted, and means also responsive after the time registered on the last one of said switches has been transmitted for restoring said sequence switch to its normal starting position.

25. In a telephone system, subscribers' lines, a

continuously operating time registering device, a transmitting apparatus for transmitting the time registering thereon, automatic progressively movable means controlled by a calling subscriber for establishing a connection between any of said subscribers' lines and said transmitting apparatus, and means in said transmitting apparatus responsive to a connection for starting the transmitting apparatus to transmit the time registered.

26. In a telephone system, subscribers' lines, a continuously operating time registering device, a transmitting apparatus for transmitting the time registering thereon, automatic progressively movable means controlled by a calling subscriber for establishing a connection between any of said subscribers' lines and said transmitting apparatus, means in said transmitting apparatus responsive to a connection for starting the transmitting apparatus to transmit the time registered, and means responsive when said connection is released for causing said transmitting apparatus to restore to its original starting position.

27. In a telephone system, a plurality of sound producing devices, automatic means for operating said devices at predetermined intervals in accordance with the time of day to simulate the striking of a clock, a microphone associated with each device for translating the sound emitted therefrom into electrical current variations, a circuit in which said current variations are manifested, and means controlled by a subscriber of the exchange for connecting his line with said circuit.

28. In a time signaling system, a plurality of registers, means for automatically resetting said registers at regular intervals so that at any given time the combined setting will be in accordance with the time of day, a sound producing device, means controlled by said registers for operating said device at intervals to produce audible time signals, a microphone for picking up said signals, and a circuit over which corresponding electrical signals are transmitted by said microphone.

29. In a telephone system, a plurality of subscribers, a time transmitting mechanism in the exchange, a sound producing device therefor operated at intervals to produce characteristic sounds indicative of the time of day, means for picking up said sounds and for translating the same into electrical current variations, a circuit for said current variations, means controlled by a calling subscriber for establishing a connection to receive said current variations, and means at the subscriber's station controlled by said current variations for reproducing the characteristic sounds.
